UNITED STATES PATENT OFFICE.

FRANK VINCENT WHYLAND, OF SALISBURY, CONNECTICUT, ASSIGNOR, BY
MESNE ASSIGNMENTS, TO ASBURY LESTER, OF NEW YORK, N. Y.

SWAGING-MACHINE.

SPECIFICATION forming part of Reissued Letters Patent No. 11,826, dated May 22, 1900.

Original No. 629,838, dated August 1, 1899. Application for reissue filed March 22, 1900. Serial No. 9,820.

To all whom it may concern:

Be it known that I, FRANK VINCENT WHYLAND, a citizen of the United States, residing at Salisbury, in the county of Litchfield and State of Connecticut, have invented certain new and useful Improvements in Swaging-Machines, of which the following is a specification, reference being had to the accompanying drawings, in which—

10 Figure 1 is a side view of my machine. Fig. 2 is a vertical central lengthwise section of the machine. Fig. 3 is a vertical cross-section of the swaging-head on line 3 3 of Fig. 2. Fig. 4 is a vertical cross-section taken through the line 4 4 of Fig. 2. Fig. 5 is an elevation partly in section, showing the stop-motion. Fig. 6 is a view, partly in cross-section, of the stationary head B and the fingers b. Fig. 7 is a plan view of the machine. Fig. 8 is a plan 20 view of spoke-wire W, showing blanks and swaged portion. Fig. 9 shows cross-section of the roller-bushing b². Fig. 10 shows roller b³.

Like letters refer to like parts throughout the several views.

25 In the drawings illustrating the devices of my invention and the best mode now known to me of arranging and applying the same (see Figs. 1 and 2) the standard A supports the stationary head B, which is the outer casing of the swaging device and is firmly held to the standard A by the cap A' and the bolts a a and nuts a' a' or in any other suitable manner. The standards and frame A⁸ support the working parts of the feeding and 30 shearing devices described below.

35 G is a driving-pulley splined at g on the hub g' of the fly-wheel G, and G² is a loose pulley on the same hub g'. The fly-wheel G', through its hub g', is fast on the tubular 40 shaft H, through the center of which and for its entire length is the wire-passage h of suitable diameter for the passage of the wire to be operated upon. The inner end of the wire-passage h is preferably contracted to the diameter of the wire W in order to guide it 45 properly to the swaging-dies J².

B' is a steel band shrunk on the inner end of the stationary head B over the fingers b to increase the resistance of fingers b to the 50 force of the hammering and swaging blows and to reinforce the blocks b'.

The stationary head B, containing the swaging device, is constructed as follows,

(see Fig. 3:) The inner face of the stationary head B is formed with a plurality of fingers b, in the spaces between which are mounted reinforcing-blocks b', (of hardened steel,) against which rest cylindrical bushings b², (of hardened steel,) which are formed with lengthwise openings in their inner faces. 60 These bushings b² contain rollers b³, (of hardened steel,) which slightly project into the central chamber b⁴ of the stationary head B. (See Fig. 3.) The tubular shaft H (see Fig. 2) projects into said chamber b⁴ and is provided at its inner end with a head or boss h', grooved transversely at h⁵ across its face, the opposite sides of the groove being equidistant from the middle of the boss h' and coincident with the lengthwise axis of the tubular shaft 65 H. The head or boss h' is centrally and axially recessed to receive the bushing h², which is set loosely in said recess. The bushing h² is grooved across its face transversely and centrally to agree with the groove across the 70 face of the head or boss h', and the inner end of the said bushing h² is centrally perforated for the wire as the same is fed into the machine. The bushing h² receives the greater proportion 75 of wear and is renewable. The hammers J, the wedges J', and the swaging-dies J² are loosely mounted in the grooves h⁵ of the boss j' and bushing h², the hammers J and dies J² being actuated by the successive contact of the cam-shaped ends j of the hammers J with 80 the inwardly-projecting peripheries of the 85 rollers b³. The wedges J' are actuated by mechanism hereinafter described.

The reinforcing-blocks b', the bushing b², the rollers b³, the hammers J, the wedges J', 90 the swaging-dies J², and the tubular-shaft bushing h² are all subject to rapid wear and require to be replaced with more or less frequency. To facilitate the substitution of 95 worn parts, the elements just above mentioned are removable and are retained in their respective positions by concentric face-plates b⁵ and b⁶, plate b⁵ being removably fixed to head B, and plate b⁶ being removably fixed to the collar or boss h' and rotating therewith 100 and having suitable holes or slots b⁹ for the reciprocation therethrough of the wedges J'.

To regulate the force of the blows delivered by the hammers J upon the dies J², I provide tapered wedges J', inserted between 105 the hammers J and the dies J², and which are

pivotedly connected with the grooved revolute wedge-carrying collar K, which has a backward-and-forward motion upon the stationary tubular support K', the same being 5 preferably a part of and projecting from a transverse bar o of the frame A³, which extends across the face and forward of the swaging devices. The collar K is actuated by the lever K², which is pivotally connected at k with the cam-lever K³. The cam-lever K³ is fulcrumed at k' on the tubular support K'. The cam-lever K³ is provided with a cam-roller k², which works with the cam K⁴. The wedges J' are forced inwardly between the 15 hammers J and the swaging-dies J² by the movement of the collar K toward the boss h', this movement being due to the push of cam K⁴ on the cam-roll k². When the portion k³ of cam K⁴ is against the cam-roll k², the spring 20 K⁵ serves to pull the wedge-carrier K and wedges J' outwardly from their most effective wedging position, so that the cam-shaped ends j of the hammers J are out of working contact with the rollers b³. One end of spring 25 K⁵ is fast to frame A³ and the other end to cam-lever K³, and the spring is distended when the inward movement of the collar K occurs.

Cam-lever K³ is provided with a suitable 30 nut K⁶ (conveniently the equivalent of a turn-buckle) to increase or decrease its length, so that a proper adjustment is secured for the insertion or withdrawal of the wedges J' between the hammers J and the dies J². The 35 cam K⁴ and a cam K⁷ and a worm-gear K⁸ are each supported on shaft K⁹, which is actuated through the worm K¹⁰, (see Fig. 7,) the shaft K¹¹, which carries the worm K¹⁰, passing 40 through suitable bearings in the frame A³ and the standard A and being provided with suitable driving-pulleys K¹² and K¹³. These pulleys are of different diameters to secure different speeds for shaft K¹⁶ and are each mounted on a hub K¹⁴, loose on the shaft K¹¹, 45 which is adapted to be coupled to the hub K¹⁵, which is fast on shaft K¹¹.

Cam-shaft K⁹ (see Figs. 2, 4, and 5) carries a rocker-arm K¹⁶, which has a lengthwise slot k⁴, in which there is an adjusting-block k⁵, 50 which is adjusted in its slot by the adjusting-screw L. This block k⁵ is pivotally connected by a pin l with a slide-block L', mounted in the lengthwise slot l' of the rocker-lever L², which is pivoted at l² to the base of the machine. The upper end of rocker-lever L² is loosely jointed at l³ with the connecting-rod L³ for carriage D'. That end of the rocker-lever L² with which the connecting-rod L³ is thus connected is furnished with a lengthwise opening l⁴, in which a spring l⁵ is mounted rearwardly of the pin l³. The other end of the connecting-rod L³ is adjustably connected to the carriage by means of the clamp-bolt l⁶ through the elongated slot l⁷. By this adjustment 65 the position of the carriage in relation to the wire is regulated independently of the adjustment of the slide-block L'. Rocker-

lever L² is provided with an abutment l⁸, which on the back stroke of the rocker-lever L² strikes slide-bar L⁴, carrying an inclined shoe l⁹, which co-operates with the inclined block l¹⁰ in the vertical slide-bar l¹¹ and serves to pull the slide-bar l¹¹ downwardly against the stress of a spring l¹², mounted above the horizontal abutment l¹³, through which the 70 slide bar or rod l¹¹ passes, the rod being provided with a fixed collar l¹⁴ to engage the upper end of the spring l¹². The upper end of the slide-rod l¹¹ extends into the path of an abutment l¹⁵ on the bottom of the carriage D'. 80 On the back stroke of the carriage the pin l³ engages the spring l⁵ in the outer end of the connecting-rod L³ and compresses it slightly. As this spring is compressed the shoe l⁹ moves the slide-rod l¹¹ downwardly and out of the 85 path of abutment l¹⁵, so that the carriage D' moves again and carries the wire which has been operated on and is still clamped by the jaws D² D³ (on carriage D') a distance equal to that portion of the spoke which is called 90 the "blank." The carriage on its back stroke is first brought to rest by engagement of abutment l¹⁵ with the upper end of the slide-rod l¹¹. It is at this time that the wire ceases to move lengthwise and that the swaging-dies 95 J² form the shoulder x', (see Figs. 2 and 8,) the swaging-dies J² acting during the interval that the wire is at rest to form a nicely-finished shoulder x' instead of a more or less imperfectly-formed shoulder, as would happen if the wire were moved continuously. The interval required for compressing the spring l⁵ and pulling the slide-bar l¹¹ out of the path of abutment l¹⁵ practically corresponds to the interval required to form the 100 shoulder x', and when the shoulder x' is completed the carriage moves on to its outermost limit, the extent of this movement corresponding to the length of the blank.

The jaws D² D³ are loosely pinned at their 110 butt-ends to the upright d of carriage D', the free end of one jaw facing the free end of the other jaw and both jaws pointing toward the swaging mechanism. The range of movement of one of the jaws is limited by a stop 115 d', mounted in a bracket d² of the carriage D'. The other jaw, which is opposite its mate, is moved toward the wire to clamp it by the cam d³ on the end of rod d⁴, which carries a roll d⁵, that runs in the lengthwise raceway d⁶ of the vertically-movable frame d⁷. This frame d⁷ is guided in vertical ways d⁸ d⁹ in the frame A³. Frame d⁷ is provided with a dependent cam-roll d¹⁰, which works with the cam K⁷. When the cam K⁷ is in operative position, the frame d⁷ is at its lowest position, falling downward in its ways by gravity and the under jaw D² then gravitating away from the wire W. When the swell of the cam K⁷ rises against the cam-roll d¹⁰, the frame d⁷ is lifted, 125 carrying the under jaw D² against the wire W and clamping it against the upper jaw D³. The dependent cam-roll d¹⁰ is adjustable on the frame d⁷ in order to suit wires of differ-

ent diameters, the adjusting-screw d' serving, with the adjustable cam-roll d^{10} , to regulate the jaws to wires of different diameters and also to so adjust the jaws that their working ends are operative on work kept central in relation to the swaging mechanism.

To secure any desired length of blank in a given length of spoke, the carriage D' is formed with a lengthwise slot d^{11} , and the upright d , to which the jaws $D^2 D^3$ are pivoted, is provided with a horizontal side plate d^{12} , through which a clamp-bolt d^{13} passes into and through the slot d^{11} . Carriage D' is provided with a horizontal slide plate f , having a lengthwise slot f' , through which a clamping-screw f^2 extends to lock the plate in adjusted position on the carriage. This plate f carries an upright f^3 , in which is mounted the wire-guide f^4 , this guide having a hole through it for the passage of the wire W . One of its functions is that of a shear-blade. The movable member f^5 of the shearing mechanism is a vertically-reciprocating bar having a hole through it for passage of the wire, and when the movable member slides upwardly, the wire being through the hole in guide f^4 and also through hole in member f^5 , the wire is cut off, as will be readily understood. Cutting member f^6 is actuated by the rocker-lever f^6 , fulcrumed on a stud f^7 on the carriage D' . One arm of the rocker-lever f^6 works in a hole in the movable cutting member f^5 , and its outer end is provided with a roller f^8 , which runs in the raceway d^6 of the vertically-movable frame d^7 . The up-and-down motions of this frame d^7 effect the requisite reciprocations of the movable cutting member f^6 .

Carriage D' is movable lengthwise of the machine toward and away from the swaging mechanism and is mounted on ways d^{18} in frame A^8 .

Considering the mechanism in the position shown in the drawings, a spoke is supposed to have been just severed at the middle of a blank-section of the wire, the movable cutting member f^5 is just returned to its position of rest, and the jaws $D^2 D^3$ released from the wire, so that the carriage is free to carry the jaws and the severing mechanism toward the swaging mechanism, through which it is supposed the second of two continuous blank-sections has just been drawn. These two continuous blank-sections are marked x^8 and x^4 in Fig. 2. The carriage now moves back toward the swaging-head and the wedges enter inwardly between the hammers and dies to the full extent provided and the jaws pass over the wire, which passes outward through the coincident holes in the wire-guide f^4 and the hole in the movable cutting member f^5 . When the carriage reaches the limit of its inward movement, jaws $D^2 D^3$ seize at or nearly on the swaged portion of the wire, and at the same instant the shearing device is actuated and severs the spoke just pulled through by the feeding device, and the carriage now moves back with the wire, which is being constantly

hammered or swaged as it is pulled through the swaging mechanism, until the abutment l^{15} strikes the stop or slide rod l^{11} . Then, as above described, the carriage takes a fresh start rearward and the swaging-dies stop work, allowing the formation of two continuous blanks. The jaws are again opened and the carriage moves inward to grasp and pull another spoke and the operations are repeated.

The main advantages of the herein-described machine are the simplicity of the construction of the swaging-head, permitting quick and easy renewal of worn parts and the momentary stopping of the carriage while the second shoulder is being formed and the subsequent completion of the back stroke of the carriage at the same rate of speed that it had at the first part of its rearward movement. Heretofore the final movement of the carriage has been accelerated just before the second shoulder was finished, with the result that the wire was carried too swiftly to permit proper swaging of the spoke about an inch in front of the second shoulder, this part of the spokes heretofore swaged being characterized by a rough or ridge-like conformation, deemed highly objectionable by those skilled in the art.

I claim as my invention—

1. In a swaging-machine, the combination with a stationary head having a plurality of fingers, of reinforcing-blocks and of bushings, a reinforcing-band surrounding and binding said parts together, rollers contained within said bushings, a boss formed with a groove, a tubular shaft rotating within said stationary head and carrying said boss, hammers sliding in the outer part of said groove, swaging-dies sliding in the inner part of said groove, wedges entering said groove between said hammers and said dies, a wedge-carrying collar, a tubular shaft for the same, a slide controlling said collar, a lever for operating the slide, a cam controlling said lever, and means to rotate said cam, substantially as specified.

2. In a swaging-machine, the combination with the boss formed with a transverse groove, the hammers and swaging-dies and intermediate wedges therein, and means for operating the same, of the stationary head surrounding the swaging devices and having a plurality of fingers integral with and projecting from the said head, reinforcing-blocks fixed between the said fingers, cylindrical bushings between and backing against the fingers and the reinforcing-blocks, and rollers within the bushings and against which rollers the hammers strike in the operation of the swaging devices, substantially as set forth.

3. In a swaging-machine, the combination of a supporting-frame, swaging mechanism, coacting jaws, a jaw-carrying carriage, mechanism for reciprocating said carriage, mechanism for temporarily arresting said carriage at an intermediate point in its travel while

said swaging mechanism is in operation, and mechanism for releasing the carriage from said arresting means and completing the movement of said carriage in the same direction from said intermediate point to the end of its travel, substantially as specified.

4. In a swaging mechanism, the combination of a main stationary frame, a carriage sliding in said frame, a rocker-arm, a rocker-arm shaft, means to rotate said shaft, a rocker-lever, a slide-block, means to adjust said slide-block, a link connecting said carriage and said rocker-lever, a spring interposed between said rocker-lever and said link, a lug on said rocker-lever, a slide-bar in the path of said lug, a shoe fast on said slide-bar, a slide-rod formed with a beveled foot arranged to be engaged by said shoe, a spring controlling said slide-rod, and an abutment on said carriage arranged to strike said slide-rod when the latter is extended, substantially as specified.

5. In a swaging-machine, the combination with a stationary head, rotary swaging devices therein and means for operating the same, of a transverse bar of the frame extending across the face and forward of the swaging devices, a stationary tubular support connected to the said transverse bar and projecting therefrom toward the swaging devices, a revolute collar surrounding the said tubular support, wedges pivotally connected to the said revolute collar and acting with the swaging devices and means for moving the said revolute collar and the wedges longitudinally upon the said tubular support, substantially as set forth.

6. The combination in a swaging-machine, with the stationary head, the swaging devices within the same and means for operating the said swaging devices, of concentric face-plates secured to the face of the swaging-device support and rotating therewith, a transverse bar of the frame in front of the swaging devices, a tubular support integral with the transverse bar and occupying a position axially with the center of the swaging devices, the said transverse bar being perforated to agree with the opening in the tubular support, a revolute collar upon the tubular support, wedges pivotally connected upon opposite sides of the revolute collar and extending forward through the concentric face-plates to engage the swaging devices, and means for moving the said revolute collar and wedges longitudinally of the tubular support, substantially as and for the purposes set forth.

7. The combination in a swaging-machine with the stationary head, the swaging devices within the same and means for operating the said swaging devices, of concentric face-plates secured to the face of the swaging-device support and rotating therewith, a transverse bar of the frame in front of the swaging devices, a tubular support integral with the transverse bar and occupying a position axially with the center of the swaging devices, the

said transverse bar being perforated to agree with the opening in the tubular support, a revolute collar upon the tubular support, 70 wedges pivotally connected upon opposite sides of the revolute collar and extending forward through the concentric face-plates to engage the swaging devices, means for moving the said revolute collar and wedges longitudinally of the tubular support, a lever 75 engaging the revolute collar and a guide therefor, a spring-actuated lever and a connection therefrom to the aforesaid lever and a cam for actuating the latter lever, substantially as and for the purposes set forth.

8. The combination in a swaging-machine with the stationary head, the swaging devices within the same and means for operating the said swaging devices, of concentric face-plates 85 secured to the face of the swaging-device support and rotating therewith, a transverse bar of the frame in front of the swaging devices, a tubular support integral with the transverse bar and occupying a position axially with the 90 center of the swaging devices, the said transverse bar being perforated to agree with the opening in the tubular support, a revolute collar upon the tubular support, wedges pivotally connected upon opposite sides of 95 the revolute collar and extending forward through the concentric face-plates to engage the swaging devices, and means for moving the said revolute collar and wedges longitudinally of the tubular support, a lever engaging the revolute collar and a guide therefor, a spring-actuated lever and a connection therefrom to the aforesaid lever, and a cam for actuating the latter lever, and means substantially as specified for adjusting the cam-lever with reference to the cam and for adjusting the relation of the cam-lever to the other lever for controlling the action of the wedges, substantially as set forth.

9. In a swaging-machine, the combination 110 with the stationary head, of a tubular shaft and integral head or boss at one end of said tubular shaft revolute in the said stationary head, the face of the said head or boss being centrally and transversely grooved and provided with a central axial recess, a bushing h^2 adapted to fit said central recess, the said bushing being transversely grooved to agree with the transverse groove in the boss or head and centrally and axially perforated, hammers fitting and sliding in the transverse groove of the said head or boss, swaging-dies fitting and sliding in the transverse groove of the said bushing h^2 , and wedges entering the said transverse groove between the hammers 125 and dies, and means for supporting the wedges and for revolving the said tubular head its boss and the bushing h^2 , substantially as and for the purposes set forth.

Signed by me this 7th day of March, 1900. 130

FRANK VINCENT WHYLAND.
